Attorney

UNITED STATES PATENT OFFICE

VIRGIL A. SCOFIELD, OF COCHISE, ARIZONA

NEEDLE THREADER

Application filed March 15, 1924. Serial No. 699,474.

The present invention provides an article whereby to quickly thread a needle, said article attachable to the spool upon which the thread is wound, thereby enabling the spool to perform the function of a handle for convenient and ready manipulation of the device when in active operation, and the spool also serving as a holder whereby the needle threader may be conveniently at hand and 10 not liable to be misplaced or lost.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is a perspective view of a needle threader embodying the invention, showing the same attached to a spool of thread,

Figure 2 is a perspective view of the threader, showing the needle in position to receive the thread,

Figure 3 is an end view of the device,

Figure 4 is a detail view showing more clearly the manner of attaching the threading element to the holder, and

Figure 5 is a perspective view of the threading element.

Corresponding and like parts are referred to in the following description and designated in the several views of the drawings by like reference characters.

The article comprises essentially two parts, a holder and a threading element, the holder preferably consisting of a sheet metal blank bent into the form substantially as shown. The threading element consists of a short length of extremely fine wire bent into the form of a loop and having the extremities of the folded portions attached to the holder, the parts adjacent the fold brought close together and flattened, as indicated at 1, and the part intermediate the ends spread, as indicated at 2, whereby to provide ample space

for the ready passage of a thread 3. By flattening the sides of the threading element at the folded end 1, provision is had for drawing the thread through the eye of a needle 4.

The holder for the threading element comprises a cylindrical portion 5 which is adapted to be inserted in the opening of a spool 6, upon which the thread is wound. The cylindrical portion 5 has an edge portion 7 inwardly folded to grip the terminal portions of the threading element, thereby securing the loose ends and at the same time serving to secure the threading element to the holder. The outer portion of the holder is flattened and the flat end 8 projects beyond the flattened end 9 to form a guard which assists materially in positioning the needle 4 preliminary to passing the threading element through the eye thereof. The folded end 1 of the threading element projects a short distance beyond the flattened end 9 and terminates short of the outer end 8, whereby provision is had for properly positioning the needle when adjusting the latter to receive the threading element preliminary to passing the same through the eye of the needle. The intermediate portion of the holder is cut away, as indicated at 10, so as to expose the intermediate spread or open portion 2 of the threading element, whereby the thread 3 may be readily passed therethrough after the needle has been slipped upon the threading element, as indicated most clearly in Figure 2.

After the threading element has been passed through the eye of the needle, the latter is moved thereon to admit of the thread 3 being passed through the open portion 2, after which the needle is moved outwardly to clear the threading element, the latter serving to draw the thread through the eye of the needle, as will be readily appreciated.

What is claimed is:

A needle threader made primarily from a blank, said blank being formed into a split cylindrical portion adapted to fit the bore of a spool, the device being cut away above the cylindrical portion and above the cut away portion having relatively close flattened portions, one of the flattened portions extending above the other to provide a guard, a thread-

ing element consisting of a fine wire in the form of a loop disposed between said flattened portions, a portion of said loop being disposed in said cut away portion, the loop being fastened to the upper edge of the cylindrical portion.

5 In testimony whereof I affix my signature.
VIRGIL A. SCOFIELD.
